DESIGN FOR A RUBBER HEEL OR SIMILAR ARTICLE

Sidney G. Wager, Elyria, Ohio, assignor to The I. T. S. Company, Elyria, Ohio, a corporation of Ohio

Application October 1, 1945, Serial No. 122,439

Term of patent 14 years

(Cl. D7—5)

To all whom it may concern:

Be it known that I, Sidney G. Wager, a citizen of the United States, residing at Elyria, in the county of Lorain and State of Ohio, have invented a new, original, and ornamental Design for Rubber Heels or Similar Article, of which the following is a specification, reference being made to the accompanying drawing, forming a part thereof.

In the drawing:

Fig. 1 is a bottom plan view of a rubber heel, showing my new design;

Fig. 2 is a side elevational view of the design illustrated in Fig. 1 having a portion thereof cut away to show the recessed portion of Fig. 4;

Fig. 3 is an end elevational view of the design illustrated in Fig. 1; and

Fig. 4 is a top plan view of the design illustrated in Fig. 1.

I claim:

The ornamental design for a rubber heel or similar article, substantially as shown.

SIDNEY G. WAGER.
